UNITED STATES PATENT OFFICE.

ALDEN E. OSBORN, OF NEW YORK, N. Y.

INTERNAL-COMBUSTION ENGINE.

1,315,192.

Specification of Letters Patent. Patented Sept. 2, 1919.

Application filed September 22, 1916. Serial No. 121,532.

To all whom it may concern:

Be it known that I, ALDEN E. OSBORN, a citizen of the United States, and a resident of New York city, county and State of New York, have invented certain new and useful Improvements in Internal-Combustion Engines, of which the following is a specification, reference being had to the accompanying drawings, forming a part thereof.

10 My invention relates to internal combustion engines, and has for one object to provide an engine that shall be simple in construction and reliable in operation.

In my Patent No. 1,212,391, Jan. 16, 1917, 15 I have shown and described an engine which possesses many advantages and is particularly simple and reliable. My present invention pertains to engines of the same general character and it has been my aim to increase 20 the power developed by the engine, by providing an additional admission port which is uncovered by the main piston near the end of its working stroke, and which cooperates with the intermediate port to improve 25 the operation of the engine, particularly for certain classes of service; as, for example, for aviation purposes.

Other objects and advantages of my invention will be set forth hereinafter, and 30 in order that my invention may be thoroughly understood, I will now proceed to describe the same in the following specification and then point out the novel features thereof in appended claims.

35 Referring to the drawings:

Figure 1 is a sectional elevation of an engine arranged and constructed in accordance with my invention and constituting an embodiment thereof. The section is taken on 40 the line 1—1 of Fig. 2.

Fig. 2 is a sectional plan view, taken on the line 2—2 of Fig. 1.

Fig. 3 is a partial elevation corresponding to Fig. 1, of a modified structure which also 45 embodies my invention.

The structure of Figs. 1 and 2 comprises a cylinder 10 in which operates a piston 11, a crank case 12, a crank shaft 13, a crank pin 14, a valve cylinder 15, a slide valve 16 50 therein, a valve crank 17 and connecting rods 18 and 19.

The valve crank shaft 20 to which the valve crank 17 is secured is operatively connected to the crank shaft 13 by gears 55 designated 21—22—23, the gears being so proportioned that the valve crank shaft is

operated at one-half the speed of the crank shaft of the engine. Other means may, of course, be employed for this purpose.

An exhaust port 24 opens into the valve cylinder 15 near the combustion chamber 25 of the engine and an inlet 26 opens into the valve cylinder near its opposite end, as clearly shown in Fig. 1.

The slide valve 16 has the form of a hollow cylindrical piston and is provided with a transverse partition 27 which divides off a chamber 28. There are three sets of openings 29—30—31 in the chamber 28 which are adapted respectively to register with admission ports 32 and 33 which open into the engine cylinder 10, and the inlet 26 in the valve cylinder 15. The admission port 32 opens into the cylinder at an intermediate point in the piston stroke while the admission port 33 opens into the cylinder substantially at the end of the piston stroke.

If the port 33 is used alone there are many disadvantages which are clearly understood by those skilled in this art; for example, there is relatively high vacuum produced in the engine cylinder throughout the greater part of the intake stroke since the admission port is only open at the end of the stroke. On the other hand, by utilizing the admission port 33 in addition to the port 32 the amount of power developed by the engine can be somewhat increased, with a minimum of complication.

My invention is obviously not limited to an engine having a valve cylinder and piston valve and as an example of other types of engine to which my invention is applicable, I have shown an engine having a valve of the sleeve type, in Fig. 3 to which reference 95 may now be had. In this structure 35 designates the engine cylinder which is provided with an exhaust port 39. Immediately within the cylinder is a sleeve valve 40 having through passages 41 and 42 which are adapted to register with the admission ports 36 and 37 respectively. The engine piston 43 operates within the sleeve valve in a well known manner, the sleeve valve being driven at half the speed of the piston as in the arrangement of Fig. 1.

As shown in Fig. 3, I prefer to utilize a plurality of openings through the sleeve valve and through the cylinder wall in order to increase the size of the effective admission 110 openings.

The engines shown operate in substan-

tially the same manner and the operation of Fig. 1 will first be discussed. Assuming that the parts occupy the positions in which they are illustrated, and that the crank shafts 13 and 20 are rotating in a counterclockwise direction, the engine is in position to start on its working stroke. The exhaust port 24 is closed by the valve 16 and the ports 32 and 33 substantially register with the admission 5 openings 29 and 30. During the working stroke the crank 17 moves through an angle of substantially 90 degrees and the valve moves outwardly a sufficient amount to close the ports 32 and 33 before they are uncovered 10 by the main piston. The next stroke of the engine is the exhaust stroke, the valve 16 being moved during the next quarter turn of the valve crank so as to uncover the port 24 and permit the burnt gases to escape. 15

20 During the next stroke of the engine which is the suction stroke, the valve moves inwardly so as to close the exhaust port to bring the ports 29 and 32 and the ports 30 and 33 into register by the time they are 25 covered by the main piston 11.

Just at the end of the suction stroke the valve 15 has advanced sufficiently to close the upper admission port to prevent fuel being forced backwardly during the next 30 stroke of the engine which is the compression stroke. The lower port is closed by the main piston in the arrangement illustrated, but if desired the valve may be arranged to close both admission ports. At the end of 35 the compression stroke, the parts occupy the positions in which they are shown in the drawings.

The operation of the engine shown in Fig. 3 will be clearly understood from the 40 description of the operation of that of Fig. 1. The two inlet ports which are shown as communicating with a single inlet opening, may be connected with separate passages communicating with the same or different 45 sources of gas supply, or one may communicate with the gas supply while the other opens into the air alone.

My invention may obviously be embodied in structures other than those illustrated 50 and I intend that only such limitations be imposed as are indicated in appended claims.

What I claim is:

1. An internal combustion engine comprising a cylinder having a combustion chamber at one end, a piston, and an exhaust port, an admission passage opening into the cylinder at an intermediate point in the piston stroke, a second admission passage opening into the cylinder near the outer end of the piston stroke, a single valve, and means for actuating the valve to open the admission passages in conjunction with the piston during the suction stroke. 55

60 2. An internal combustion engine com-

prising a piston, a cylinder having three independent ports communicating therewith, one of which is at an intermediate point in the piston stroke and a second of which is near the end of the piston stroke, 75 a valve, and means for actuating the valve to open said intermediate and end ports in conjunction with the piston during one outward stroke of the piston and to close both of said ports independently of the piston during another outward stroke of the piston. 75

3. An internal combustion engine comprising a cylinder having a combustion chamber at one end, a piston, an admission passage opening into the cylinder at an intermediate point in the piston stroke, a second admission passage opening into the cylinder near the end of the piston stroke, an exhaust port opening into the combustion chamber, a valve, and means for operating the valve at one-half the speed of the main piston to independently control the exhaust port, to open the admission passages in conjunction with the main piston during the suction stroke, and to close one 80 of said passages at the end of said suction stroke independently of the piston. 85

4. An internal combustion engine comprising a cylinder having a combustion chamber at one end, a piston, an admission 95 passage opening into the cylinder at an intermediate point in the piston stroke, a second admission passage opening into the cylinder near the end of the piston stroke, an exhaust port opening into the combustion 100 chamber, a piston valve, and means for operating the piston valve at one-half the speed of the main piston to independently control the exhaust port, to open the admission passages in conjunction with the main piston 105 during the suction stroke, and to close one of said passages at the end of said suction stroke independently of the piston. 105

5. An internal combustion engine comprising a cylinder having a combustion 110 chamber at one end, a piston, an admission passage opening into the cylinder at an intermediate point in the piston stroke, a second admission passage opening into the cylinder near the outer end of the piston stroke, 115 a valve, and means for actuating the valve to open the admission passages in conjunction with the piston during the suction stroke, and to close one of said passages independently of the piston during the compression stroke. 120

6. An internal combustion engine comprising a cylinder having a combustion chamber at one end, a piston, an admission passage opening into the cylinder at an intermediate point in the piston stroke, a second admission passage opening into the cylinder near the outer end of the piston stroke, a valve, and means for actuating the valve to open the admission passages in conjunction 125 130

tion with the piston during the suction stroke, and to close said intermediate passage independently of the piston during the compression stroke.

5 7. The combination in a four-cycle engine with the cylinder and a piston in the cylinder, of a valve, an exhaust port arranged to be opened and closed at properly timed intervals by movement of the valve, 10 and inlet ports provided in the cylinder at

different levels below the combustion chamber, said inlet ports arranged to be opened and closed at properly timed intervals by movement of the valve and piston, all constructed and arranged so that when the explosion occurs all said inlet ports are below the head of the piston.

In witness whereof, I have hereunto set my hand, this 27 day of June, 1916.

ALDEN E. OSBORN.
